B. J. DRIVER.
COIN CONTROLLED ADVERTISING DEVICE.
APPLICATION FILED OCT. 28, 1912.

1,097,541.

Patented May 19, 1914.

UNITED STATES PATENT OFFICE.

BOEN J. DRIVER, OF WINSLOW, ARIZONA.

COIN-CONTROLLED ADVERTISING DEVICE.

1,097,541.

Specification of Letters Patent. Patented May 19, 1914.

Application filed October 28, 1912. Serial No. 728,136.

To all whom it may concern:

Be it known that I, BOEN J. DRIVER, a citizen of the United States, residing at Winslow, in the county of Navajo and State of Arizona, have invented a new and useful Improvement in Coin-Controlled Advertising Devices, of which the following is a specification.

This invention relates to advertising devices, and the principal object thereof is to provide an advertising device in which an advertiser may disclose a certain amount of information, and the address of the advertiser or further information will be disclosed upon the deposit of a coin commensurate with the value of the information obtained.

It is also an object to provide means for changing the advertising matter and the information conveyed by the operation of the vending device.

It is a further object to provide means for locking the device in positive closed position until the lock is operated by a coin, the return to the locking position being accomplished by the release of the received coin.

In the drawings accompanying this specification Figure 1 is a front elevation of a frame with a battery of coin controlled devices embodying this invention, one of the doors being shown in open position. Fig. 2 is an enlarged central longitudinal section on the line 2—2 of Fig. 1 including the open device. Fig. 3 is a transverse section through one device on line 3—3 of Fig. 2, looking in the direction of the arrows. Fig. 4 is a section on the line 4—4 of Fig. 2, looking in the direction of the arrows. Fig. 5 is an enlarged detail view of the weighted catch.

More specifically in the drawings, 6 designates a cabinet shown as built of wood, provided with a drawer 7 which is supplied with a suitable lock and a plurality of advertising devices 8 mounted on the door frame 9, this door frame forming a closure to the recess 10 which communicates with the drawer 7.

As before stated, a plurality of advertising devices are mounted on the door 9, these devices being preferably inclined as clearly shown in Fig. 2, so that a greater number may be included in the door way by the overlapping of the guideways necessary for the sliding sash shown. Hinged doors may be substituted, however, for this sliding sash

pivoted at their sides or top without departing from the salient features of the invention. This sliding sash 11 is provided with a sight opening 12 and the coin slot aperture 13, and is adapted to slide in the inclined guideways 14 in a vertical door frame so that the return is accomplished by its own weight after having been lifted from the normal and secured position. To lift the sash a suitable knob 15 is provided, and a card retainer 16 is placed to the rear of the glass covered sight opening 12 in which cards may be inserted from the upper open side of the holder.

Secured to the rear of the sliding sash 11 is the coin receiver 17 preferably formed of metal, provided with the flanges 18 by which the latter are secured to the sash opening, the receiver registering with the slot opening 13 in the sash, and preferably inclined downward so that the coin inserted will readily slide to the limiting stops, operating when in this position the releasing means to the catch.

The coin stop is preferably formed of a piece of wire of suitable stiffness formed in the general shape as shown, with the body portion 19 pivoted in the bracket 20 secured to the casting 17 provided with arms 21 which are bent downward to form the fingers 22 thereon projecting into the coin slot and the path of the coin through suitable aperture cut in the upper wall of the coin receiver 17, the lower wall serving as a stop to the fingers 22.

In the body portion and oppositely disposed from the arms is the finger 23 formed at an angular relation to the main portion of the stop so that the depression of this portion lifts the arms 21 with their fingers 22. Placed to the rear of this slide in the path of the guideways 14 is the frame 25 which is provided with the beading 26 which forms a limiting support for the sash in its normal position. This frame is parallel with the guideways and is also provided with a card holder 27 which is open at its upper edge to receive suitable cards. Mounted on the rear of the frame which is provided with the stud 28, is the pivoted latch member 29 pivoted on the stud 28 by means of the screw 30. This latch member is preferably operated by means of the weighted arm 31 which extends sufficiently downward and inward from the pivot as to throw the engaging hook 32 of the catch

in positive engagement with the strike 33 formed on the coin receiver 17. The coin receiver is provided with a recess on the edge adjacent the catch and the strike which 5 extends a sufficient distance into the structure to expose the edge of a proper coin, the edge of which bears on the inclined face 35 formed on the catch member 39, the weight of the coin being sufficient to overcome the 10 weight of the lever 31 and throw the catch 32 out of engagement with the strike.

A stop 34, at the upper portion of the frame 26 is placed in line with the path of the finger 23, and in such a relation that it 15 engages therewith when the sash is lifted, a suitable opening being formed in the frame 25 so that the coin receiver and its attachments have a clear path, and cards may be introduced into the card holder 16 20 when the sash is raised.

The operation of this device and its peculiar adaptability to this class of advertising will now be described, the invention being especially designed as a mechanical 25 employment agency, the data regarding the desired employment of a certain artisan being printed on a card and inserted in the holder 16, the data giving the address or location where this particular artisan may 30 obtain work being placed on a card which is inserted in the card holder 27. When it is desired to disclose this latter information, a suitable coin, previously designated, is dropped into the coin receptacle through the 35 slot 13 and the coin takes up against the fingers 23, at the same time releasing by its own weight the catch 32, and the sash may be lifted to disclose the information desired, exposed on the card in the card holder 27. 40 As the sash is lifted before it reaches its upper limit, the finger 23 engages with the stop 34, lifting the fingers 22, permitting the coin to drop into the drawer 7, and the releasing of the handle by the operator permits 45 the sash to drop after a copy is made, or the information read. The sash drops by its own weight, and is engaged and locked

by the latch 32 until such time as it is again released by the introduction of the proper coin.

50

What I claim is:

1. A coin controlled closure, comprising a slidable support having a coin slot therein, a frame adapted to receive said support, a coin receiver mounted on said support and 55 registering with said slot, a coin operated catch on said frame, and a coin stop on said coin receiver adapted to be released by the movement of said support.

2. A coin controlled closure, comprising 60 a slidable support having a coin slot therein, a frame adapted to receive said support, a coin receiver mounted on said support, a coin operated catch on said frame, and a pivoted coin stop on said coin receiver 65 adapted to be released when the support is moved in said frame to drop said coin.

3. A coin controlled closure, comprising a slidable support having a coin slot therein, a frame adapted to receive said support, a 70 coin receiver mounted on said support, a pivoted coin operated catch on said frame, and a coin stop on said receiver adapted to be released when the support is moved in said frame to drop said coin.

75

4. A coin controlled closure, comprising a slidable support, a grooved frame adapted to receive said support, an inclined coin receiver mounted on said support, a coin operated catch pivoted on said frame, a weight 80 secured to said catch to return the same to the locking position, a pivoted coin stop mounted on said coin receiver, and means to release said coin catch when the latter is engaged with the upper portion of the 85 grooved frame.

In witness that I claim the foregoing I have hereunto subscribed my name this 21st day of October, 1912.

BOEN J. DRIVER.

Witnesses:
